UNITED STATES PATENT OFFICE

ADAM STEWART, JAMES McCLUSKEY, AND HERBERT GATES REID, OF NORTH BAY, ONTARIO,
CANADA.

STARTING-VALVE.

No. 892,194.

Specification of Letters Patent.

Patented June 30, 1908.

Application filed October 18, 1906. Serial No. 339,585.

To all whom it may concern:

Be it known that we, ADAM STEWART, machinist, JAMES McCLUSKEY, engineer, and HERBERT GATES REID, engineer, all of the 5 town of North Bay, in the district of Nipissing, Province of Ontario, Canada, have invented certain new and useful Improvements in Starting-Valves, of which the following is the specification.

10 Our invention relates to improvements in emergency exhaust valves for locomotives, and the object of the invention is to provide a valve of this class which will not be liable to get out of order by reason of the head 15 becoming detached from the valve stem and in which the head when not in use will work easily in the cylinder without any wear and will only become tight at the end or working point of the stroke and it consists essentially 20 of a cylindrical head provided with an enlarged outer end having an inclined inner face and a reduced threaded inner end, an expanded ring having an inclined outer face surrounding the body of the head, a pair of 25 split rings interposed between the expander ring and the enlarged portion of the head and having inclined faces designed to coact with the inclined face of the expander ring and inclined face of the head, a locking device 30 for the expander ring and nuts located in the valve stem to each side of the head, as hereinafter more particularly explained in the following specification.

Figure 1 is a sectional view through a portion 35 of the engine showing the valves arranged for working the engine on single expansion. Fig. 2 is a similar view to Fig. 1 showing the valves arranged for working the engine at compound. Fig. 3 is an enlarged 40 sectional detail of the emergency exhaust valve head shown in the single expansion position. Fig. 4 is a similar view to Fig. 3 showing the valve head at the compound position. Fig. 5 is an enlarged perspective 45 detail of the emergency exhaust valve head. Fig. 6 is a longitudinal section through the emergency exhaust valve head. Fig. 7 is a detail of the locking bars.

In drawings like letters of reference indicate corresponding parts in each figure.

A is the frame of the engine, B is the receiver pipe connecting the high and low pressure cylinders, C the steam inlet, D the

intercepting valve, E the exhaust to the atmosphere. 55

F is a passage leading into the exhaust E.

G is the emergency exhaust valve operating in the chamber G' having a shoulder 2.

H is a steam or air filled pipe controlled by a valve in the cab of the engine. 60

When it is desired to work the engine at simple air is admitted into the chamber G' forcing the valve G open and allowing steam to exhaust through the passage F, from the receiver B to the atmosphere. 65

I is a valve stem of the emergency exhaust valve and K is the inner or piston head of the valve.

It has been found that by the use of the old form of piston or valve head where the 70 expander rings are in contact with the internal surface of the casing for the full length of the stroke that the casing becomes worn into the form indicated by dotted lines in Figs. 3 and 4 on account of the rings sticking at the 75 beginning of the stroke. When the valve becomes worn and a new one inserted it will not fit the casing at this part and will allow air to leak past to such an extent that the air pump will either become worn out in compensating for such leakages or the valve will 80 not operate. If the air pressure cannot be kept up the engine has to be run in compound while drifting that is when the engine is running down hill with the steam shut off, and 85 in consequence burns as much coal drifting as when running under steam. Also in the old form the nut J³ securing the piston to the valve is liable to break off and the compression spring of the valve would then force the 90 head off the stem rendering the valve inoperative. To overcome these objections we have devised a special form of piston head, which we will now describe.

J is a nut secured on the valve stem I and 95 provided with a shoulder J'.

K' is the compression spring of the valve which is located between the valve casing and the nut and surrounding the stem of the valve.

K is the head provided with the enlarged portion L' having a beveled or inclined face L². The head L is also provided with a reduced threaded portion L³.

L⁴ is a split ring having a flat face L⁵ and 105 an inner beveled or inclined face L⁶ designed

to rest on the inclined face L^2 of the head. L^7 is a split ring also, provided with a flat face L^8 and an inclined face L^9 . The flat face of the ring L^7 is designed to contact with 5 the flat face of the ring L^4 .

- L^{10} is an expander ring loosely surrounding 10 the piston head and provided with an outer inclined face L^{11} designed to contact with the inclined face L^9 of the split ring L^7 .
 M is an internally threaded holding ring 15 designed to screw onto the reduced portion of the head and partially overlap the inner face of the expander ring L^{10} to hold the same on the head.

- N is a locking bar provided with a threaded stem N' and a pin N^2 .

- N^3 is an internally threaded hole formed in 20 the end of the head and N^4 is a hole formed partially in the head and partially in the holding ring M . The stem N' is screwed into the hole N^3 and the pin N^2 is then sprung into place into the hole N^4 . By this means the holding ring is securely locked in place.

- Having described the principal parts involved 25 in our invention we shall briefly describe the operation of the same. When it is desired to change the engine from compound to simple the air is admitted to the chamber G' forcing the piston and valve in 30 the direction indicated by arrow until the expander ring L^{10} striking the shoulder 2 of the valve casing and moving longitudinally against the split rings L^7 , L^8 , wedging them against the machine face L^2 of the piston and 35 expanding them against the walls of the casing. It will be seen that the tightening of the piston occurs at the end of the stroke of the valve, the piston moves freely in the cas-

ing during the major portion of its stroke thus avoiding any unnecessary wear, which 40 would enlarge at the inner diameter of the casing at any point and produce a leakage of air which would decrease the sensitiveness of the valve and be detrimental to the air pump. It will also be seen that should the 45 holding nut of the valve break off that it would not affect the working thereof. Should such a thing occur the head would be held in place by the air pressure forcing it on the valve rod. The compression spring in our 50 construction bears on the nut and therefore does not force the head off the stem as in the old construction.

It will be understood that a head such as described may be used for any purpose 55 where the piston works from one end and operates a valve or performs work at the other end.

What we claim as our invention is:

In a valve of the class described, the combination with the casing, having a shoulder therein intermediate of its length and an air inlet, and the valve stem, of a piston head having an enlarged end having an inclined face, a wedge ring surrounding the piston 60 and designed to strike the shoulder formed in the casing, packing rings having inclined faces corresponding respectively to the inclined faces of the wedge ring and enlarged end, as and for the purpose specified.

ADAM STEWART.

JAMES McCLUSKEY.
